CLAIM

The ornamental design for a light, as shown and described.

DESCRIPTION

FIG. 1 is a top perspective view of the light, showing a first embodiment of our new design.

FIG. 2 is a bottom perspective view of the first embodiment.

FIG. 3 is a top view of the first embodiment.

FIG. 4 is a bottom view of the first embodiment.

FIG. 5 is a front view of the first embodiment.

FIG. 6 is a rear view of the first embodiment.

FIG. 7 is a right-side view of the first embodiment.

FIG. 8 is a left-side view of the first embodiment.

FIG. 9 is an enlarged view of a portion of the light from the first embodiment.

FIG. 10 is a top perspective view of the light, showing a second embodiment our new design.

FIG. 11 is a bottom perspective view of the second embodiment.

FIG. 12 is a top view of the second embodiment.

FIG. 13 is a bottom view of the second embodiment.

FIG. 14 is a front view of the second embodiment.

FIG. 15 is a rear view of the second embodiment.

FIG. 16 is a right-side view of the second embodiment; and, FIG. 17 is a left-side view of the second embodiment.

The broken lines shown in the drawings illustrate portions of the light which form no part of the claimed design.

1 Claim, 16 Drawing Sheets
